UNITED STATES PATENT OFFICE.

NATHAN ALLEN GIBBONS, OF MARTINS FERRY, OHIO, ASSIGNOR TO WHITTAKER-
GLESSNER COMPANY, OF WHEELING, WEST VIRGINIA, A CORPORATION OF WEST
VIRGINIA.

HOG TROUGH.

1,407,404.

Specification of Letters Patent. Patented Feb. 21, 1922.

Application filed October 6, 1921. Serial No. 505,711.

To all whom it may concern:

Be it known that I, NATHAN ALLEN GIBBONS, a citizen of the United States of America, and resident of Martins Ferry, county 5 of Belmont, and State of Ohio, have invented certain new and useful Improvements in Hog Troughs, of which the following is a specification.

This invention relates broadly to troughs 10 of the character employed for feeding and watering live stock, and more specifically to a hog trough.

The primary object of the invention is to provide a sheet-metal hog trough which 15 possesses great strength and durability and which is relatively inexpensive to manufacture.

A further object is to provide a device 20 of the character mentioned having a knock-down form adapting it for shipment and storage in small space and which may be readily set up in condition for use by any person without the exercise of more than ordinary skill.

With these and other objects in view, the 25 invention resides in the features of construction, arrangement of parts and combinations of elements which will hereinafter be fully described, reference being had to the accompanying drawings, in which—

Figure 1 is a top plan view of the invention;

Figure 2 is a side elevation of the same;

Figure 3 is an end elevation;

Figure 4 is a cross section on line 4—4, 35 Fig. 2, showing the intermediate supporting leg;

Figure 5 is a partial section on line 5—5, Fig. 2, showing the body brace;

Figure 6 is an enlarged cross section of 40 said body brace;

Figure 7 is a longitudinal section on line 7—7, Fig. 1;

Figure 8 is a similar section showing an 45 end leg in its initial entering position, and—

Figure 9 is a section on line 9—9, Fig. 2.

Referring to said drawings, 1 indicates 50 a trough body, approximately U-shaped in cross section, having downwardly and inwardly inclined end walls 2 secured in place by any suitable means, as by double seaming, as shown at 3 in Fig. 7. An open outwardly turned bead or roll 4 is formed upon the upper edge of each of said end walls 2, and embraced by said bead or roll

is a smaller roll 5 formed upon the upper edge of an end supporting leg 6. Said leg comprises an approximately rectangular panel 6^a designed to rest more or less closely against the end wall 2 and which has a greater height than that of said end wall. A horizontal outwardly extending flange 6^b formed on the lower edge of said leg constitutes a foot which seats upon the ground, floor, or other surface. Extending inward from said panel 6^a are lateral wings 6^c of substantially triangular form, the upper horizontal edges of which are designed to seat in underlying supporting relation to rolls 7 formed upon the lateral edges of the trough body 1, said rolls 7 having the under portions thereof cut away throughout a suitable distance, as shown at 8, to permit said edges of the wings to assume such relation. An upright tongue 9 carried upon the extreme inner end of each wing 6^c is designed to project through a slit 10 provided therefor in the adjacent roll 7, and then to be turned outward into seated clamping relation to said roll for maintaining said leg 6 in place.

Provided midway between the ends of the trough is an intermediate supporting leg 11 formed of a sheet-metal strap and consisting of an arcuately curved central seat portion 11^a adapted to conformably receive thereon the bottom portion of the trough body 1, opposite downwardly and outwardly inclined legs 11^b, outwardly extending foot portions 11^c designed to rest upon the same plane as the feet 6^b of legs 6, and upwardly and inwardly inclined brace members 11^d, the latter being terminated by outwardly turned rolls 11^e which are received within the embrace of the rolls 7 of the trough body. Said rolls 11^e are introduced within said rolls 7 at an end of the latter and said leg 11 is then readily slipped along the trough body to its proper position. Manifestly, in the case of a long trough a plurality of legs 11 may be disposed at suitable intervals throughout the length of same to afford the desired stability.

One or more braces 12 may be provided for preventing relative spreading of the sides of the body 1 intermediate the ends of the latter. Said brace 12 comprises a narrow strip of metal disposed transversely across the top of the trough body and having its opposite ends 12^a turned down into 110

clamping relation to the rolls 7 of the latter. To increase the rigidity of said brace 12, that portion of the body thereof located between said ends 12^a is preferably bent into 5 arcuately curved form in cross section, as is shown in Fig. 6.

As is obvious, the trough may be shipped in knock-down form and readily assembled by any person without the exercise of special skill.

To apply the legs 6, the hook-like rolls 5 thereof are initially engaged with the rolls 4 of the end walls while said legs are disposed substantially in the reversed position shown 15 in Fig. 8. Said legs are then swung downward to the position shown in Figs. 2 and 7 in which the panels 6^a substantially parallel the end walls 2, the upper edges of the wings seat under the rolls 7 of the trough body, and 20 the tongues 9 project through the slits 10 of said rolls 7, after which said tongues are bent into overlying interlocked relation to said rolls.

The intermediate leg or legs 11 are applied by introducing the terminal beads 11^a thereof within the embrace of said rolls 7 at one end of the latter and then sliding the same along the trough body to the desired position or positions.

30 What is claimed is—

1. A sheet-metal trough comprising a trough body having rolls formed on its lateral edges, end walls provided on said body and having rolls formed on the upper edges 35 thereof, and detachable legs at the opposite ends of said body, each leg comprising an approximately upright panel and lateral wings, said panel having a roll on its upper edge adapted to be interlocked with the roll

of the adjacent end wall, and means for interlocking said wings with the trough body.

2. A sheet-metal trough comprising a body of trough shape having lateral rolls formed upon its upper edges, end walls carried by said body and having open rolls 45 formed on their upper edges, detachable panel-like legs having their upper edges underlying and interlocked with the rolls of said end walls, and lateral wings formed on said legs and interlocked with the rolls of 50 said body.

3. A sheet-metal trough comprising a body of trough shape having lateral rolls formed upon its upper edges, end walls carried by said body and having open rolls 55 formed on their upper edges, detachable panel-like legs having their upper edges underlying and interlocked with the rolls of said end walls, and lateral wings formed on said legs and interlocked with the rolls of 60 said body, said legs extending below the level of the bottom of said body and having terminal seating flanges at their lower edges.

4. The combination with a sheet-metal trough body having lateral rolls formed 65 upon its upper edges, of a supporting leg consisting of a sheet-metal strip bent to form a central trough-underlying seating portion, oppositely disposed foot portions, and inclined brace members, the latter terminated 70 by beads which are slidably disposed within the embrace of the rolls of the trough body.

In testimony whereof, I affix my signature in presence of two subscribing witnesses.

NATHAN ALLEN GIBBONS.
